(57) **CLAIM**

The ornamental design for a wheel for automobile, as shown and described.

DESCRIPTION

FIG. 1 is a perspective view of a wheel for automobile showing my new design; and,

FIG. 2 is a front view thereof.

The claimed design is indicated by the relatively dark portions in the figures, while the de-emphasized greyscale portions form no part of the claimed design.

1 Claim, 2 Drawing Sheets

FIG. 1

FIG. 2
